US00D913242S

(12) **United States Design Patent** (10) Patent No.: **US D913,242 S**
(45) Date of Patent: **** Mar. 16, 2021**

(54) **USB TYPE-C RECEPTACLE**

(71) Applicant: **Eaton Intelligent Power Limited**,
Dublin (IE)

(72) Inventors: **Luis F. Salas**, Fayetteville, GA (US);
Brandon Jeremy Rogers, Senoia, GA
(US); **Saivaraprasad Murahari**,
Peachtree City, GA (US); **Sushant Dilip**
Raut, Maharashtra (IN)

(73) Assignee: **EATON INTELLIGENT POWER
LIMITED**, Dublin (IE)

(**) Term: **15 Years**

(21) Appl. No.: **29/690,488**

(22) Filed: **May 8, 2019**

Related U.S. Application Data

(62) Division of application No. 29/572,982, filed on Aug.
2, 2016, now Pat. No. Des. 853,333.

(51) **LOC (13) Cl.** **13-03**

(52) **U.S. Cl.**

USPC **D13/133**

(57) **CLAIM**

The ornamental design for a USB type-C receptacle, as
shown and described.

DESCRIPTION

FIG. 1 is an isometric view of the USB type-C receptacle;
FIG. 2 is another isometric view of the USB type-C receptacle;

FIG. 3 is a front view of the USB type-C receptacle;

FIG. 4 is a left side view of the USB type-C receptacle;

FIG. 5 is a right side view of the USB type-C receptacle;

FIG. 6 is a back view of the USB type-C receptacle;

FIG. 7 is a top view of USB type-C receptacle; and,

FIG. 8 is a bottom view of the USB type-C receptacle.

In the drawings, the broken lines are for the purpose of
illustrating portions of the USB type-C Receptacle that
forms no part of the claimed design.

1 Claim, 8 Drawing Sheets
